UNITED STATES PATENT OFFICE.

NORMAN B. IRVING, OF PHILADELPHIA, PENNSYLVANIA.

AUTOMATIC MEASURING DEVICE FOR LIQUIDS.

Application filed October 21, 1926. Serial No. 143,165.

My invention relates to an automatic measuring device for liquids, and has for its object to provide a means for delivering predetermined quantities of liquids in a simple and direct manner, particularly so as to provide such a means whereby two different quantities may be predetermined by the valve apparatus, either one of which quantities may be drawn off at the option of the person operating the valve.

With the above and other objects in view, my invention consists in the combination and arrangement of parts hereinafter described and claimed, it being understood that, within the limits of what is claimed, changes in the precise embodiment shown, may be made without departing from the spirit of the invention.

In the drawings—

20 Figure 1 is a sectional view of a liquid container having my invention applied thereto;

25 Figure 2 is a front elevation of the same, partly in section;

30 Figure 3 is a section along the line 3—3 of Figure 1, showing a top plan view of my device with parts thereof shown in section;

35 Figure 4 is a section along the line 4—4 of Figure 1.

40 Figure 5 is a detail of the automatic air valve.

45 Referring now more particularly to the drawings, A refers to a container for liquids, such as a cream urn, having provided there-

50 in the false bottom 10. Positioned beneath the false bottom are two measuring compartments B and C. The said compartments may be of any capacity according to the option of the person constructing the device,

55 but in the embodiment shown, the compartment B is shown larger than the compartment C, thus, the compartment B might be or one pint capacity and the compartment C of one-half pint capacity. A portion of the false bottom 10 is depressed to form a

60 seat 11 for the cylindrical plunger valve D and is continued up and over the said plunger valve as at 12, so as to thereby form a cylindrical housing E in which is slidably positioned the said plunger valve D. The

65 tongue 14, positioned on the plunger valve D, is adapted to slidably engage the slot 13 provided medially the upper surface of the housing E, whereby the said plunger valve D is prevented from rotating in the said

70 housing E.

The seat 11 has provided therein and near the inner end thereof, the ports 15 communicating the urn A with the measuring compartments B and C; the said ports being 75 opened by the plunger valve D when in its outward position and closed when the said plunger valve is in its inward position. The seat 11 also has provided therein and near the outer end thereof, the ports 16, and the 80 upper portion 12 of the housing E has provided therein, directly above the said ports 16, the ports 17, communicating with the pipe 18 hereinafter described. The ducts 19 are provided in the plunger valve D suitably to communicate the ports 16 with the ports 17 when the said plunger is in its inward position.

Provided in the false bottom 10 and communicating the measuring compartments B 75 and C with the vertical pipes 20, is the aperture 21 formed on its underside suitably to receive the stoppers 22, the said stoppers being constructed of cork or other buoyant material and provided with the rubber seat 23 on the upper side of said stopper. The upwardly extending stem 24 is positioned on the stopper 22 and passes through the guide 25 positioned in the pipe 20, the upper end of the said stem being formed into the loop 26 so as to limit the downward travel of the said stem and stopper. The upper end of the pipe 20 communicates with the bifurcated pipe 27 passing upwardly through the urn A and communicating with the atmosphere. 90

95 Affixed to the front walls of the measuring compartments B and C is the valve structure F having vertically positioned therein the rotatable plug 28 positioned in the plug seat 32 and provide with the discharge duct 29 passing upwardly therethrough and extending at right angles suitably to register with the ports 30 and 31, the port 30 communicating with the measuring compartment B and the port 31 communicating with the measuring compartment C; the said ports opening into the plug seat 32 diametrically opposite each other, whereby the said discharge duct 29 may communicate with either one of the said ports 30 and 31, or with neither one of them by rotating the said plug 28 by means of the handle 33. 100

105 In the operation of my device, the urn A containing the liquid to be measured, is caused to communicate with the measuring

compartments B and C, by moving the plunger valve D outwardly so as to uncover the ports 15, whereupon liquid will flow into the said compartments, the displaced air 5 being permitted to pass out through the aperture 21, and pipes 20 and 27 to the atmosphere; but when the compartments are filled with the liquid, the buoyance of the stoppers 22 will cause them to rise and close 10 the apertures 21 whereby entrance of the liquid into the said pipes 20 and 27 will be prevented and a measured quantity of liquid will be contained in the measuring compartments B and C and no more. When the 15 compartments are filled with the liquid, the plunger valve D is pushed inwardly, closing the ports 15 aforesaid, and causing the pipes 20 and 27 to be communicated with the said measuring compartments through the ports 20 17, ducts 19 and ports 16, whereby the said measuring compartments are maintained at atmospheric pressure so that the liquids contained therein may be withdrawn by rotating the plug 28 suitably to communicate 25 the discharge duct 29 with the port 30 and compartment B or the port 31 and compartment C at the option of the person using the device.

It is obvious that as the level of the liquid 30 falls in the compartment, the stopper 22 will descend and open the aperture 21 suitably for a repetition of the before described sequence of operations, but until the said stopper has thus descended and opened the aperture 21, the port 16, duct 19 and port 17 will serve to prevent a vacuum being formed in the compartment.

I claim:

1. The combination with an urn provided 40 with a false bottom, of a plurality of measuring compartments positioned beneath the said false bottom, a valve seat formed in said false bottom, a housing formed over said valve seat, a plunger valve slidably positioned in said housing; means for communicating said urn with the said measuring compartments for filling the same, by the outward movement of said plunger valve; buoyantly operable means for communicating said measuring compartments, when being filled, with the atmosphere. 50 whereby said compartments may be shut off from the atmosphere when filled and the measured quantity of liquid retained in said compartments; means for communicating said measuring compartments, when being filled, with the atmosphere by the inward movement of said plunger valve; and means for causing the optional discharge of any of said compartments.

2. The combination with an urn provided with a false bottom, of a plurality of measuring compartments positioned beneath the 60 said false bottom, a valve seat formed in said false bottom, a housing formed over said valve seat, a plunger valve slidably positioned in said housing; means for communicating said pipes vertically positioned on said false bottom, means for communicating said pipes with the atmosphere, apertures provided in said false bottom communicating said pipes with said measuring compartments, means for communicating said third mentioned ports with said pipes, ducts provided in said plunger valve communicating said second mentioned ports with said third mentioned 65 ports when said plunger valve is in its inner position whereby said compartments may be maintained at atmospheric pressure when liquid is being withdrawn from said compartments, guides positioned in said pipes, vertically extending stems slidably positioned in said guides, dependent stoppers positioned on said stems suitably to close said apertures when in their upward position, the said stoppers being constructed of 70 buoyant material, so as to float upward when liquid is admitted in said compartments, whereby displaced air may be permitted to escape to the atmosphere but any liquid prevented from entering said pipes; and means 75 for causing the optional discharge of any of said compartments.

2. The combination with an urn provided with a false bottom, of a plurality of measuring compartments positioned beneath the 80 said false bottom, a valve seat formed in said false bottom, a housing formed over said valve seat, a plunger valve slidably positioned in said housing; means for communicating said urn with the said measuring compartments for filling the same, by the outward movement of said plunger valve; buoyantly operable means for communicating said measuring compartments, when being filled, with the atmosphere. 90 whereby said compartments may be shut off from the atmosphere when filled and the measured quantity of liquid retained in said compartments; means for communicating said measuring compartments, when being filled, with the atmosphere by the inward movement of said plunger valve; and means for causing the optional discharge of any of said compartments.

In testimony whereof I affix my signature.

NORMAN B. IRVING.
